ROTARY LAWN MOWER

Henry L. Heineke, Springfield, Ill.

Application July 10, 1956, Serial No. 42,194

Term of patent 14 years

(Cl. D40—1)

Des. 180,282

PAGE 2

FIG. 3.

FIG. 4.

FIG. 5.

FIG. 6.

Fig. 1 is a perspective view of a rotary lawn mower embodying my new design, viewed particularly from the right front side thereof;

Fig. 2 is a perspective view, viewed particularly from the left front side thereof;

Fig. 3 is a perspective view looking particularly from the left rear side thereof;

Fig. 4 is a perspective view looking particularly from the right rear side thereof;

Fig. 5 is a top plan view thereof; and

Fig. 6 is a bottom plan view thereof.

The essential features of the design reside in the portions shown in full lines.

In Figs. 2, 3, 4, 5 and 6 of the drawings, the handle and cable are shown broken away for convenience of illustration.

I claim:

The ornamental design for a rotary lawn mower, substantially as shown and described.
